UNITED STATES PATENT OFFICE

WALTER W. SIBSON, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA

FABRIC-TREATING MACHINE

Application filed September 12, 1929. Serial No. 392,056.

This invention relates to fabric treating machines and, more particularly, to that type or class of machines commonly known as tenter-dryers for stretching and drying textile materials.

In machines of the class referred to, the cloth treated is customarily stretched and held to the desired width, during the drying process, in parallel horizontal runs between which heating coils are located to effect the drying operation. Such coils are usually steam heated and are, generally, uniformly distributed intermediate the successive runs of cloth and, as an obvious consequence, said cloth becomes hotter and hotter, as the drying proceeds, and finally emerges from the machine in a highly overheated or "baked" condition. Cloth so treated, when delivered from the machine is usually wound up into large rolls or bolts, which require considerable time to cool down, with the disadvantage that, as such cooling takes place from the outside surfaces and edges inwardly, there is frequently developed in said cloth a streaky or shaded condition detrimental not only to the finished appearance but also to its commercial value.

The primary object of my invention is to overcome the noted objectionable features by passing the drying medium transversely of the material treated in one direction across one region or section of the drying chamber, and then returning it in the reverse direction across the other section of said chamber.

Another object of this invention is the provision in a fabric treating machine, of the type referred to, of control means whereby the circulation of drying medium may be variably accommodated to different widths of material.

A further object of the invention is to provide, in a machine of the character specified, means whereby a supply of fresh cooling medium is counter-traversed through that portion of the machine segregated to the final run of the material treated; and associated means by which a variable quantity of the cooling medium, with its chilling effect partially reduced, is diverted into the

main treating chamber to replenish the exhausting moisture-laden atmosphere.

My invention still further comprehends other features of construction which, in addition to those above stated, are fully set forth hereinafter and specifically recited in the claims.

The invention is illustrated in a preferred form in the drawings accompanying and forming a part of this specification; although it will be readily appreciated that such drawings are purely illustrative and by way of enabling my invention to be clearly understood.

In the drawings:

Fig. I is a more or less diagrammatic side view of a tenter-drying machine embodying the present improvements, minor portions being broken out to better disclose underlying features.

Fig. II is a sectional plan view, taken on the plane designated II-II in Fig. I.

Fig. III is a similar plan view, taken on the plane indicated by the arrows III-III in Fig. I.

Fig. IV is a longitudinal vertical section through the treating chamber.

Fig. V is a transverse vertical section, taken on the plane designated V-V in Fig. I.

Fig. VI is a view, similar to Fig. I, of a modified form of the invention; and,

Fig. VII is a sectional view, taken on the plane marked VII-VII in the preceding illustration.

Referring more in detail to Figs. I-V, the numeral 1 comprehensively designates an inclosure or drying chamber of conventional construction, the same embodying a top or roof 2, bottom or floor 3, side walls 4 and end walls 5. This chamber 1 is conveniently of rectangular formation and subdivided by a vertically-disposed longitudinal partition 6, extending downwardly from the roof 2, in parallelism with one of the side walls 5, to thereby—in part—define a vertical section 7 in which is located the heater unit 8. This heater unit 8 may be of any well known type, but is shown as consisting of a pipe bank through which is circu-

100

lated a heating medium, such, for example, as steam. Suitable controls—not shown—may be fitted in connection with the heater unit 8, so that various drying temperatures may be obtained in the chamber 1, for differing service conditions.

Co-extensive with the lower edge of the vertical partition 6 is a fixed or stationary lateral partition 9 which, as will be best appreciated from Fig. V, extends horizontally part-way across the chamber 1, from the aforesaid partition 6, intermediate a pair of the runs of the material M being treated. This lateral partition 9, it is to be noted, is of a width to leave a substantial clearance between its free edge and the proximate track rails 10 over which the "tenter" conveyor chains 11 are progressed; and co-operative with said partition I provide a sliding member or shutter-plate 12, the purpose of which is to vary the circulatory flow of the drying medium for differing widths of material M treated. In other words, when a narrower width of material M than that indicated is to be treated, the sliding shutter-plate 12 is moved, by appropriate means not shown, over the lateral partition 9 toward the vertical partition 6 in an obvious manner, and vice versa. Attention is also directed to the fact that the two elements 9, 12 jointly divide the inclosure space into upper and lower circulatory sections 13, 14, respectively, for a purpose later on explained.

Paralleling the inclosure floor 3 and located above the final run of the material M, on its way to the delivery end of the machine, is a horizontal partition or inner floor 15 that sets apart a cooling compartment or duct 16, through which atmospheric air—preferably from outside the building in which the machine is located—is forced by means of a suitable blower 17. Discharge of the cooling air from the compartment 16 is by way of an appropriate outlet 18 exhausting to atmosphere or otherwise, as desired; and it is to be particularly noted that in connection with this outlet 18 I provide an adjustable damper 19, whereby a portion of the air flowing through the compartment 16 is diverted, in a semi-preheated condition, into the heater section 7. This diversion of semi-preheated air from the compartment 16 into the main inclosure embracing the sections 7, 13 and 14, controllably replenishes the moisture-laden exhaust therefrom; as well as increasing the efficiency of the machine appreciably by avoidance of "chilling" the section 7, more particularly. There is quite an advantage accruing to delivery of the material M from the machine in a cooled condition by passage of its final run through the compartment or duct 16, as it not only has a better "feel" but also a much better appearance; and, furthermore,

does not tend to develop streaks or uneven shades: while it is in a much better condition to absorb and retain the proper amount of moisture regain essential to certain classes of material.

Circulation and re-circulation of the drying medium is effected by means of a series of vertically rotating fans 20 journaled in housings 21 secured to the hereinbefore referred to vertical partition 6. The shafts 22 for the fans 20 pass through truncate fittings 23, intermediate the partition 6 and the proximate side wall 4, where they are provided with suitable means, such as the belt drives 24 shown, for co-ordination with a counter-shaft 25, having a main drive pulley 26 connecting with any convenient source of power.

Progression of the material M through the inclosure 1 is effected by means of suitable mechanism—not shown—driven by a chain and sprocket drive 27, for example, connecting with a variable speed device 28, in turn co-ordinated by a drive 29 with the counter-shaft 25 above referred to. In order to prevent too great an accumulation of highly saturated air in either or both of the drying sections 13, 14, I provide an exhaust fan 30, conveniently mounted on the roof 2 of the inclosure 1, and operatively connected to the counter-shaft 25 by a suitable drive 31, thereby to remove the moist air from said inclosure, as well as to maintain the proper drying conditions within the machine.

In some forms of tenter-driers it is desirable that the treating inclosure be subdivided so as to set up and maintain differing drying temperatures and conditions practically independent of one another. Such a machine is illustrated by the modified form of my invention shown in Figs. VI and VII, and it is to be noted that all those parts corresponding with the preceding descriptive matter are similarly distinguished by like reference numerals with the added suffix "a", in order to avoid unnecessary repetitive description. In all major respects the inclosure 1^a, of the just referred to views, conforms with that previously described excepting the addition of a horizontal partition 32 which completely separates said inclosure into relatively independent upper and lower treating sections 33, 34, respectively; while a cooling compartment 16^a is provided therebelow, as before set forth. Each of the treating sections 33, 34, is in turn subdivided as before described and fitted with a heater unit 8^a, circulating fans 20^a and shutter-plates 12^a; while communication between said sections is solely afforded, insofar as circulation of the treating medium is concerned, by way of a connecting conduit 35, with a damper control 36. This damper control 36 renders

possible the maintenance of a certain drying temperature and condition in the upper treating section 33 independent of the conditions prevailing in the lower section 34, as the respective fan systems 20^a and heater units 8^a may be controlled and operated independently of each other in an obvious manner, while the general circulation of treating medium through the entire machine remains continuous as before described.

In the embodiment of my invention under consideration, the lower series of fans 20^a are co-ordinated by belt drives 37, 38—Fig. VI—for operation from the counter-shaft 25^a; while the upper series of fans 20^a are driven by belts 39, 40 from a second counter-shaft 41, in turn driven from the first mentioned shaft 25^a by an appropriate drive 42.

Material to be treated is fed into the machine from a suitable source by passage over appropriate guide rolls 43 and tensioning means 44, following the course generally indicated by the arrows thereon in Fig. IV.

While passing through the upper section 13, of Figs. I to V inclusive, the material is subjected to heated air driven transversely thereacross by the fans 20, and during passage through the lower section 14 by a counter or reverse flow of the circulating hot air drawn thereacross by the said fans for re-passage about the heater unit 8 and constant re-circulation in an obvious manner. A similar course obtains in the modified form of my invention shown by Figs. VI and VII, with the additional advantage that when it is desired to use a greater amount of air circulation and higher drying temperature at the commencement of the treating operation or in the upper section 33, and less air circulation at a lower temperature toward the finish, or during passage of the material M, through the lower section 34 the same is readily accomplished by the means hereinbefore referred to. Such conditions, however, may be reversed if desired, while the damper 36 serves to regulate a controllable flow of the air from the lower section 34 to the upper section 33.

Following proper drying of the material M it finally passes through the cooling compartment 16 or 16^a and emerges from the inclosure 1 in a highly satisfactory condition for rolling into bolts or other form for storage, moisture regain, or other desired purpose or treatment.

While I have herein illustrated certain desirable forms of my invention, it is to be distinctly understood the same are purely exemplary, and that variations in size, shape, proportion, and the relative arrangement of the respective parts may be made without departure from the scope of the following claims.

Having thus described my invention, what I claim is:—

1. A material treating machine comprising an inclosure subdivided by partitions to define communicating treating sections; means for progressing material through said sections in paralleling runs; means circulating drying medium across the material in the respective sections; and a movable means controlling the extent of communication between said sections to accommodate differing widths of material passed through the machine. 70

2. A material treating machine comprising an inclosure subdivided by partitions to define superposed communicating treating sections and a relatively separate cooling compartment; means for progressing material through the treating sections in paralleling runs, with the final run traversing the cooling compartment; means circulating drying medium across the material in the respective superposed sections; and movable means controlling the extent of communication between the treating sections to accommodate differing widths of material passed through the machine. 80

3. A material treating machine comprising an inclosure subdivided by partitions to define superposed communicating treating sections and a relatively separate cooling compartment; means for progressing material through the treating sections in paralleling runs, with the final run traversing the cooling compartment; means circulating drying medium across the material in the respective superposed sections; means effective to flow fresh air continuously through the cooling compartment; and shutter means controlling the extent of communication between the treating sections to accommodate differing widths of material passed through the machine. 90

4. A material treating machine comprising an inclosure subdivided by partitions to define superposed communicating treating sections and a relatively separate cooling compartment; means for progressing material through the treating sections in paralleling runs, with the final run traversing the cooling compartment; means circulating drying medium across the material in the respective superposed sections; means causing fresh air to continuously flow through the cooling compartment counter-directional with respect to final run of the material; and shutter means controlling the extent of communication between the treating sections to accommodate differing widths of material passed through the machine. 105

5. A material treating machine comprising an inclosure subdivided by partitions to define superposed communicating treating sections and a relatively separate cooling 115

compartment; means for progressing material through the treating sections in paralleling runs, with the final run traversing the cooling compartment; means circulating drying medium across the material in the respective superposed sections; means forcing fresh air continuously through the cooling compartment counter-directional with respect to the advancing material; 5 means whereby a variable quantity of the fresh air, with its chilling effect reduced, is diverted from the cooling compartment into the treating sections to replenish moisture-laden atmosphere exhausted therefrom; and 10 shutters controlling the extent of communication between the treating sections to accommodate differing widths of material passed through the machine.

6. A material treating machine comprising an inclosure subdivided by partitions to define superposed communicating drying sections and a relatively separate cooling compartment; means for progressing material through the drying sections in horizontal paralleling runs, with the final run segregated to the cooling compartment; means blowing heated air transversely across certain runs of the material in one direction and returning same in the reverse direction 25 across other runs of said material; means forcing fresh air continuously through the cooling compartment counter-directionally to the advancing material; means whereby a variable quantity of the cooling air with 30 the cooling effect reduced is diverted from the cooling compartment into the drying sections; and shutters controlling the extent of communication between the respective drying sections, for the purposes specified.

7. A material treating machine comprising an inclosure subdivided by partitions to define relatively separate superposed drying chambers and an underlying independent cooling compartment; means subdividing 45 each drying chamber into communicating sections with a flanking heater section common thereto; means to progress material through the drying chambers in horizontal paralleling runs, with the final run segregated to the cooling compartment; means 50 circulating heated air transversely across the material in the drying chambers; shutters controlling the extent of communication between the respective drying chamber sections; means causing fresh air to continuously flow through the cooling compartment counter-directional to the advancing material; and means whereby a variable quantity of the cooling air is diverted from 55 the cooling compartment to replenish moisture-laden atmosphere exhausted from the machine.

8. A material treating machine comprising an inclosure subdivided by partitions 60 to define relatively separate superposed

drying chambers and an underlying independent cooling compartment; means subdividing each drying chamber into communicating sections with a flanking heater section common thereto; means to progress material through the drying chambers in horizontal paralleling runs, with the final run segregated to the cooling compartment; means circulating heated air transversely across the material in the drying chambers; 70 shutters controlling the extent of communication between the respective drying chamber sections; means causing fresh air to continuously flow through the cooling compartment counter-directional to the advancing material; means whereby a variable quantity of the cooling air is diverted from the cooling compartment into one of the drying chambers; and a flow connection between said drying chambers with a variable 75 control, for the purposes specified.

In testimony whereof, I have hereunto signed my name at Philadelphia, Pennsylvania, this 10th day of September, 1929.

WALTER W. SIBSON.
